COLLAR BLOCK WITH CREASING DEVICE

Wing J. Lee, 1322 Neck Road, Brooklyn 29, N.Y.

Filed Oct. 6, 1958, Ser. No. 765,413

4 Claims. (Cl. 223—52.1)

The present invention generally relates to a collar shaping device and more particularly to a collar block which not only shapes the collar but also engages and creases an adjacent portion of a shirt.

In certain types of laundry procedures, the shirt collar is shaped in generally a flat condition with the outer portion of the shirt being folded inwardly generally at the remote edges of the folded collar. Shaping the collar and folding the shirt by hand is time consuming and tedious and, therefore, it is the primary object of the present invention to provide a device for shaping or blocking the collar and at the same time creasing the shirt and folding the same in the desired manner.

Another object of the present invention is to provide a shirt collar blocking device having a creaser operated in response to the shaping or blocking of the collar.

Yet another object of the present invention is to provide a shirt collar blocker and creaser which is simple in construction, easy to use, operated by fluid pressure, well adapted for the purposes for which the same is intended and generally inexpensive to manufacture and maintain.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a plan view of the construction of the present invention with portions thereof broken away illustrating the details of construction thereof;

Figure 2 is a plan view taken from the underside of the device of the present invention;

Figure 3 is a longitudinal sectional view taken substantially upon a plane passing along section line 3—3 of Figure 1;

Figure 4 is a partial plan view illustrating the device of the present invention in use;

Figure 5 is a detailed sectional view taken substantially upon a plane passing along section line 5—5 of Figure 4;

Figure 6 is a plan view with portions broken away of a modified form of the present invention;

Figure 7 is a bottom plan view of the construction of Figure 6;

Figure 8 is a longitudinal, sectional view taken substantially upon a plane passing along section line 8—8 of Figure 6;

Figure 9 is a detailed sectional view taken substantially upon a plane passing along section line 9—9 of Figure 6; and

Figure 10 is a partial plan view of the device of Figure 6 prior to outward movement of the shirt engaging members.

Referring now specifically to Figures 1—5 of the drawings, the numeral 10 generally designates the collar block of the present invention which is mounted on a table surface 12 in underlying relation thereto with the device including a generally U-shaped plate member 14 having

outwardly extending flanges 16 attached to the table top surface 12 as by fastening bolts 18. Mounted on the plate 14 is a pair of elongated support brackets 20 having a transverse member 22 interconnecting the free ends thereof with one end of a cylinder 24 connected thereto with the cylinder 24 receiving a piston with a piston rod 26 extending therefrom. The piston rod 26 is connected to a transverse plate member 28 with the plate member and the transverse member 22 being interconnected by a pair of strong tension coil springs 30 which are disposed between the cylinder 24 and the supporting brackets 20. The transverse plate 28 and the piston rod 26 is connected with a slide block 32 connected with a slide plate 34 having diverging side surfaces 36 forming a can member 15 whereby the generally V-shaped member 38 defined by the diverging edges 36 is reciprocable under the plate 34 and is slidably connected thereto by virtue of a guide member 40 sliding in a slot 42 and the plate 14 and provided with an overlying plate 44 slidably engaging the top surface of the plate 14 on either side of the slot 42 with the top plate 44 being secured to the guide plate 40 and the plate 34 by fastening members 46. Slidably disposed in a transverse slot 48 is a pair of upstanding members 50 carrying a shirt collar engaging member 52 on the upper end thereof which is disposed in spaced parallel relation to the table top surface 12 and which engages into the interior of the collar 54 of a conventional shirt 56. Each laterally extending member 52 is provided with an inclined edge 58 for engagement into the inside of the collar 54. The lower end of each of the upstanding members 50 is laterally offset as designated by the numeral 60 and is connected to a lower block 62 having a roller 64 journaled thereon in the form of a follower for the cam surfaces or diverging edges 36 on the cam 38 whereby the cam 38 will move between the opposed rollers 64 for forcing the upstanding members 50 outwardly when the piston rod 26 is retracted within the cylinder 24. A tension coil spring 66 is provided between depending projections 68 on the lower 30 plate 62 which are slidable in slots 78 in the plate 14 for urging the upstanding members 50 towards each other in opposition to the cam surfaces 36.

Disposed in parallel and adjacent relation to each of the upstanding members 50 is an upstanding pivotal post 45 72 having a laterally extending arm 74 intermediate the ends thereof for positioning in the path of movement of the upstanding member 50 whereby outward and inward reciprocable movement of the upstanding member 50 will cause oscillation of the pivotal post 52 about the longitudinal axis thereof. For retaining the arm 74 against and in the path of the upstanding member 50, there is provided a tension coil spring 76 which extends between an anchor loop 78 on the plate 14 and an offset loop or eye member on the post 72. The post 72 extends 50 above the table top surface 12 and is provided with a laterally extending creasing arm 80 which is disposed above the laterally offset shirt collar engaging member 52 and which will fold the shoulder and arm portion of the shirt 56 inwardly alongside of the lower edge of the collar 54 as clearly shown in Figure 4 thus also creasing the shirt in this area due to the gripping engagement of the creasing arm 80 and the laterally extending member 52.

Referring now specifically to Figures 6—10 of the drawings, the numeral 90 generally designates a modified form of the invention including a mounting plate 92 supported in depending relation to a table top surface 94. A pair of brackets 96 extend from the mounting plate 92 and receive a pneumatic cylinder 98 having a movable piston rod 100 associated therewith. A transverse plate 102 interconnects the bracket 96 and a similar transverse plate 104 extends transversely of the piston

rod 100. A pair of tension coil springs 106 extend between the transverse members 102 and 104 for urging the same towards each other.

The transverse plate 104 and the piston 100 is connected to a longitudinally elongated slide member 108 mounted beneath the plate 92 and supported by a strap member 110. Pivotally connected to the remote end of the slide member 108 is a pair of links 112 and 114 which have their outer ends terminally and pivotally attached to elongated levers 116 and 118. One end of each of the levers 116 and 118 is pivotally anchored to the plate 92 by pivot anchor bolts 120 with the other end of each of the levers 116 and 118 being bifurcated as indicated by the numeral 120 for straddling and pivotally receiving a depending element 122 of a transversely slidable element 124 which is anchored to an upstanding member 126 having a laterally extending shirt collar gripping arm 128 extending through and disposed in parallel relation to the table top 94. Thus, as the piston rod 100 is reciprocated, the link 114 and levers 118 will cause lateral reciprocation of the upstanding members 126 and shirt collar engaging arms 128 whereby the shirt collar will be engaged and folded down flat in the usual manner.

Mounted on each of the laterally movable members 126 is a cam 130 which is orientated to engage a laterally extending arm 132 rigid with a pivotal post 134 having a creasing arm 136 on the upper end thereof which is adapted to overlie the laterally extending arm 128 when the arm 128 is moved outwardly into shirt collar engaging relation whereby the arcuately curved arm or creasing element 136 will engage and overlie the portion of the shirt immediately outwardly of and under the shirt collar 138 as indicated in Figure 6. Tension coil springs 140 interconnect the plate 92 and an offset arm 142 on the post 134 for urging the creasing members 136 to an inoperative or outwardly extending position wherein the arms 128 are then in adjacent position for positioning a shirt thereon in face down relation so that the arms 128 will be disposed within the shirt collar so that upon outward movement thereof, the shirt collar will be folded downwardly and creased in the desired manner. As the shirt collar engaging arms 128 move outwardly, they will engage the shirt collar and at the same time, the cam elements 130 will engage the inclined ends of the cam arms 132 thus pivoting the post 134 about a vertical axis and swinging the creasing arms 136 into position overlying the laterally extending arms 128 with this position being generally illustrated in Figure 6.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. A shirt forming device and creaser comprising a generally horizontal mounting plate, a pair of movable members mounted on said plate for movement in a horizontal plane above the plate, lateral projections on said members disposed in overlying relation to the plate for insertion into a shirt collar, means carried by the plate and connected with the members for urging the

members outwardly for engagement with the shirt collar, and means carried by the plate and engaged by said members for movement responsive to outward movement of said members for folding and creasing the shirt adjacent the collar, said means urging the movable members outwardly for engagement with the shirt collar including a fluid pressure operated piston and cylinder arrangement having one end thereof mounted on said plate, and means interconnecting the other end of the piston and cylinder arrangement with the movable members for moving the members outwardly when the piston and cylinder are moved longitudinally relative to each other.

5 2. The structure as defined in claim 1 wherein said means interconnecting the other end of the piston and cylinder arrangement and the movable members includes a cam plate having diverging side cam edges with the cam plate being connected with the piston of the piston and cylinder arrangement, each of said movable members having a roller thereon engaging the cam edges of the cam plate, and spring means urging the movable members towards each other and retaining the rollers in engagement with the cam edges of the cam plate whereby reciprocation of the piston will cause horizontal reciprocation of the movable members.

10 3. The structure as defined in claim 1 wherein said means interconnecting the other end of the piston and cylinder arrangement and the movable members includes a pair of elongated levers pivotally attached to the plate in spaced relation to the movable members, one end of each lever being pivotally and slidably connected to a respective movable member, and a pair of links having one end of each link connected with the piston of the piston and cylinder arrangement with the other end of each link being connected centrally to its respective lever whereby longitudinal movement of the piston will cause angular movement of the links and cause angular movement of the levers about their pivotal connection with the plate thereby providing horizontal reciprocation for the movable members.

15 4. A shirt forming device and creaser comprising a generally horizontal mounting plate, a pair of movable members mounted on said plate for movement in a horizontal plane above the plate, lateral projections on said members disposed in overlying relation to the plate for insertion into a shirt collar, means carried by the plate and connected with the members for urging the members outwardly for engagement with the shirt collar, and means carried by the plate and engaged by said members for movement responsive to outward movement of said members for folding and creasing the shirt adjacent the collar, said means for creasing the shirt adjacent the collar including a pair of laterally extending arms for engaging the shirt, and a laterally extending actuating member on each arm for engagement by its corresponding movable member, and means pivotally mounting the creasing arms on the plate for swinging movement thereof when the movable members engage the actuating members.
